UNITED STATES PATENT OFFICE.

CHARLES AUGUSTE TARRAGON, OF PORTLAND, OREGON.

BRICK-MACHINE.

SPECIFICATION forming part of Letters Patent No. 319,639, dated June 9, 1885.

Application filed October 11, 1884. (No model.)

To all whom it may concern:

Be it known that I, CHARLES AUGUSTE TARRAGON, of Portland, in the county of Multnomah and State of Oregon, have invented certain new and useful Improvements in Brick-Machines, of which the following is a full, clear, and exact description.

Reference is to be had to the accompanying drawings, forming part of this specification, in which similar letters of reference indicate corresponding parts in all the figures.

Figure 1, Sheet 1, is a plan view of the base platform of a brick-machine to which my improvement has been applied, parts being broken away and the molds and mold-carrying frame being shown as drawn out. Fig. 2, Sheet 1, is a sectional side elevation of the same, taken through the broken line $x\ x$, Fig. 1. Fig. 3, Sheet 2, is a sectional side elevation of the same. Fig. 4, Sheet 2, is a sectional front elevation of the same. Fig. 5, Sheet 2, is a plan view of a corner of a mold shown closed. Fig. 6, Sheet 2, is a plan view of a corner of a mold shown opened. Fig. 7, Sheet 2, is a side elevation of a corner of a mold, part being broken away and the sliding frame and its bars being shown in section.

The object of this invention is to facilitate the removal of bricks from the molds of brick-machines.

The invention consists in a brick-machine constructed with a sliding frame having cross-bars and carrying molds open at the corners, and provided with lugs and pins, with which engage double hooks attached to shafts carrying cam-plates and connected with sliding bars operated by arms attached to a crank-shaft held in place by a spring. With the frame carrying the molds are connected bars extending upon the opposite sides of the head-block, and provided with cleats engaging with legs attached to the guard-plate and strengthened in place by side boards, to one of which is pivoted a lever connected by a bar with one of the said extended bars, the said side boards and extended bars being connected by a spring, so that the mold-carrying frame can be readily raised and lowered, and will carry the said guard-plate with it in its outward and inward movement. The bars attached to the mold-carrying frame are connected with the side boards of the guard-plate by bars pivoted to

the rigid arms of a rock-shaft to cause the said bars to move up and down together. To the side boards connected with the guard-plate is journaled a shaft carrying water-tanks and provided with a crank-arm, whereby the head-block can be readily wet to prevent the clay from adhering thereto, as will be herein-after fully described.

A represents the base platform of a brick-machine. In the top of the platform A are formed openings B, through which the clay is forced into the molds C from the body D of the press by the mechanism described in my specification for brick-machines, for which a patent was allowed July 1, 1884, or other suitable mechanism.

The ends of the sides and ends of the molds C are mitered to each other, and to the outer sides of the said ends are attached, or upon them are formed, lugs E, the lugs at each corner projecting parallel with the miters at the said corner.

To the lugs E at each corner are attached pins F, which project above and below the said lugs, and with which engage the double hooks G, placed above and below the said lugs and attached to a rod, H. The rod H passes down between the lugs E of each pair, and to it is attached a cross-plate, I, which, when the said rod is turned to unhook the hooks G, acts as a lever or double cam to force the said lugs apart. The rods H rock in bearings in bars J, placed at the outer and inner ends of the molds C, and attached at their ends to the side bars of the frame K, which incloses the said molds C. The upper parts of the rods H are bent outward and then downward, and their ends are journaled in bearings in bars L, placed at the ends of the molds C and sliding in keepers M, attached to the inner sides of the inner and outer cross-bars of the frame K. With the middle parts of the sliding bars L are connected the upper ends of arms N, the lower ends of which are formed upon or rigidly attached to a shaft, O, rocking in bearings in the outer and inner cross-bars of the frame K. The shaft O passes through the space between the molds C, and its outer end projects and has a crank, P, attached to it for convenience in turning the said shaft to operate the sliding bars L.

To the outer cross-bar of the frame K is at-

tached a coiled spring, Q, or other suitable spring, the free end of which rests against the crank P to hold the sliding bars L pushed forward, and the hooks G in gear with the 5 pins F. The ends of the rear cross-bar of the frame K project, and to the said projecting ends are rigidly attached the forward ends of two bars, R, which extend inward along the opposite sides of the head-blocks S, placed at 10 such a distance below the platform A as to receive the frame K and the molds C, and serve as a bottom to the said molds while being filled with clay.

To the bars R are attached beveled cleats 15 T, which slide up and down along the under-cut beveled sides of the legs U, attached to the corners of the guard-plate V, and which are made of such a length as to support the said guard-plate V close against the lower 20 side of the platform A against the downward pressure of the clay, and thus prevent any clay from being forced through the openings B in the said platform when the frame K and the molds C are drawn forward to discharge the molded bricks. The cleats T and legs U cause the guard-board V to be moved forward and back by and with the frame K, and the said legs are strengthened in position by side boards, W, attached to them and to 30 the said guard-plate V.

To the board W, near its rear end, is pivoted the end of a lever, X, which extends forward to or nearly to the forward corner of the frame K, and to which is attached the 35 upper end of a connecting-bar, Y. The lower end of the bar Y is pivoted to the bar R midway between the guide-cleats T, so that by pushing downward upon the free end of the said lever X, when the frame and filled molds 40 have been drawn forward, the bars R, frame K, and molds C will be lowered, and by operating the crank P the molds will be opened and the bricks discharged upon the off-bearing board Z, placed upon suitable supports 45 or held at the forward end of the head-block.

To the middle part of the bars R are pivoted the lower ends of the short bars a, the upper ends of which are pivoted to the forwardly-projecting ends of crank-arms b, rigidly attached to the ends of a shaft, c. The shaft c is journaled to the rear parts of the boards W. The bars a, arms b, and rock-shaft c cause the two bars R and the mold-carrying frame K to move up and down squarely.

55 d are water-tanks placed beneath the forward part of the guard-plate V and attached to a shaft, e, which rocks in bearings in the forward parts of the boards W.

To one end of the rock-shaft e is attached 60 or upon it is formed a crank-arm, f, which projects forward to or nearly to the forward corner of the frame K, so that it can be readily operated when the said frame K and its attachments are drawn forward to rock the shaft e and tilt the tanks d to wet the face of 65 the head-block S, to prevent the clay when

forced into the molds C from adhering to the said head-block.

The side boards W are strengthened in position by cross-bars g h, to the rear one, h, of which is attached an arm, i, with which is connected the mechanism for moving the frame K and molds C out and in, as fully shown and described in my application for a patent allowed July 1, 1884, previously referred to.

The bars R, frame K, and molds C are raised after the bricks have been discharged by the spring j, one end of which is connected with the guard-plate V or side board W, and its 80 other end is connected with the bar R.

Having thus described my invention, I claim as new and desire to secure by Letters Patent—

1. In a brick-machine, the combination, with the sliding frame K, having cross-bars J, of the molds C, open at the corners and provided with lugs E and pins F, the double hooks G, the cam-plate I, the bent rod H, and the sliding bars L, and armed crank-shaft O, and the spring Q, substantially as herein 90 shown and described, whereby the said molds can be opened and closed by operating the said armed crank-shaft, as set forth.

2. In a brick-machine, the combination, with the platform A, having openings B, the 95 guard-plate V, the head-block S, and the frame K, carrying the molds C, of the bars R, having cleats T, the legs U, the side boards W, the lever X, and the connecting-bar Y, and spring j, substantially as herein shown 100 and described, whereby the mold-carrying frame can be raised and lowered and will carry the said guard-board with it in its outward and inward movements, as set forth.

3. In a brick-machine, the combination, 105 with the bars R, attached to the mold-carrying frame K and the side boards W, of the rock-shaft c, having rigid arms b, and the connecting-bars a, substantially as herein shown and described, whereby the two bars R are made 110 to move up and down together, as set forth.

4. In a brick-machine, the combination, 115 with the head-block S, and the side boards W, connected with the guard-plate V, of the water-tanks d, the shaft e, and its crank-arm f, substantially as herein shown and described, whereby the said head-block can be readily wet to prevent the clay from adhering thereto, as set forth.

5. In a brick-machine, the combination, 120 with a sliding frame and molds carried in said frame, of cranked shafts, devices connected with said cranked shafts and the molds, for locking together and separating said molds at their corners, and of devices for operating 125 the said cranked shafts, substantially as herein shown and described, whereby the bricks will be discharged from the molds, as set forth.
